[57] CLAIM

The ornamental design for a drop light holder, as shown and described.

DESCRIPTION

FIG. 1 is a front, top and right side perspective view of a drop light holder showing my new design;
FIGS. 2 and 3 are respectively top and bottom plan views thereof;

FIGS. 4 and 5 are respectively front and rear elevational views thereof;

FIGS. 6 and 7 are respectively right and left side elevational views thereof.

The broken line showing of a drop light in FIG. 1 is for illustrative purposes only and forms no part of the claimed design.
